UNITED STATES PATENT OFFICE.

LOUIS EMILE ANDRÉ GILLIER, OF TROYES, FRANCE.

VAPORIZING DEVICE FOR WEAVING APPARATUS.

1,106,299.

Specification of Letters Patent.

Patented Aug. 4, 1914.

Application filed October 27, 1913. Serial No. 797,699.

To all whom it may concern:

Be it known that I, LOUIS EMILE ANDRÉ GILLIER, a citizen of the French Republic, residing at Troyes, France, have invented 5 a certain new and useful Vaporizing Device for Weaving Apparatus, of which the following is a specification.

This invention relates to a vaporizing device by means of which threads (more particularly silk threads) can be treated with vapor at the moment of wearing. This device is chiefly characterized by means which reduce the escape of steam from the apparatus, and also prevent the rise of temperature 10 in the weaving room. These means chiefly bring about the condensation of the steam introduced into the chamber through which the thread passes for treatment with vapor, by utilizing for the purpose a circulation of cold water which moreover forms a non-conducting screen round said chamber. These means also render it possible to prevent the drops of water produced by the condensation of the steam, from reaching 15 the thread.

The vaporizing chamber through which the thread passes and into which steam is admitted, is arranged in an expansion and condensation inclosure with which it is in 20 open communication. This inclosure is formed by a double wall which surrounds and surmounts the vaporizing chamber and is fed through the top. The inner walls of the inclosure are in contact with the refrigerating chamber, so that water trickles 25 on the said walls and is collected at the lower portion of the said inclosure from which it is subsequently discharged. The threads, in order to get into the inner vaporizing chamber, pass through small orifices made in the outer wall of the water circulation chamber and pass through large passages which are in the latter chamber. The water cooled walls of the said passages produce a sufficient fall of temperature for 30 considerably reducing the passage of steam through the inlet and outlet orifices for the thread. In the interior of the condensation inclosure, these passages are extended, and 35 in combination with the roof on the vaporizing chamber, prevent the drops of condensed water from falling on the thread during its passage.

In the construction described by way of example, the water circulation chamber surrounding the vaporizing chamber, is formed by two parallel vertical walls on which a hollow cover is placed which does not close the said chamber, but forms a supply tank. 40 Pipes passing through the refrigerating chamber, are closed outside by a cover provided with a central opening for the passage of the thread, and are beveled inside and project under the eaves of the aforesaid roof on the vaporizing chamber. The vaporizing and condensation chambers are 45 in communication with the outside by means of water discharge pipes provided on their respective bottoms. The inner walls of the circulation chamber constitutes a condenser, 50 and water trickles down them from openings provided near the top.

A construction according to this invention is shown, in which—

Figure 1 is a cross-section, and Fig. 2 is 55 a longitudinal section, and Fig. 3 a plan.

The apparatus chiefly comprises a casing *a* with double walls through which pass pipes *b* having their inner ends beveled downwardly and inwardly, and opening into the central inclosure *c*. The pipes *b* are closed outside by plugs *e* in which are provided orifices *f* affording a passage to the thread or 60 threads to be treated with vapor. In the said inclosure a vaporizing chamber *g* is arranged surmounted by a sloped roof *h* and supported above the bottom of the casing *a*, on distance pieces *i* through which can pass 65 water branches *j* or steam branches *k*. The inner chamber *g* is provided with large 70 openings *l* opposite the pipes *b*. Collector gutters *m* are arranged on the edges connecting the vertical walls of the vaporizing chamber with the slopes *h*. The chamber *g* has a water discharge pipe *j* which opens at 75 a certain distance above its bottom, and a steam supply pipe or pipes *k*, the axis or axes of which are respectively arranged in a vertical plane containing the orifices *f*. The steam supply pipes *k* are covered respectively by a cap *n* in the lateral wall of 80 which inlet openings *o* are provided.

The inclosure *c* is closed by a hollow cover *p*, the flange *q* of which projects downward so as to dip into the chamber in which the 85 water circulates. This chamber communi- 90

cates with the inclosure *c* by means of ori-
fices *r* provided in the upper portion of the
inner walls and is supplied with water from
a feed pipe *t* by means of conduits *s* passing
5 through the flange of the hollow cover *p*.
Moreover, the inclosure *c* is placed in com-
munication with the atmosphere by means
of a pipe *u*, the orifice of which is situated
at a certain level above the bottom.

10 The thread or threads which pass into the
vaporizing chamber *g* along the line *x*—*x*
through the orifices *f* are exposed to the
action of low pressure steam (about 200 gr.
above atmospheric pressure) supplied
15 through the pipes *k* filling the said chamber.

Steam passes from the chamber *g* through
the openings *l* into the expansion and con-
densing chamber *c*. The water supplied to
the hollow cover *p*, forms a cooling layer,
20 the level of which is determined by the pos-
ition of the orifices *s* through which water
passes into the chamber *a*, and circulates
owing to differences of density. Water ren-
dered luke-warm by its contact with the in-
25 ner wall of the chamber, rises and passes
through the holes *r* into the steam expansion
and condensing chamber *c*. It trickles on
the wall, collects at the bottom and is dis-
charged through the pipe *u*. Nevertheless
30 there is left on the bottom a layer of water,
the level of which is limited by the height
of the orifice of the pipe *u* from the bottom.

The steam which was contained in the in-
closure *c*, is condensed by its contact with
35 the cold walls of the chamber *a*, and by mix-
ing with the cold water trickling along the
said walls. The products of condensation
which are also flowing on the slopes *h* of
40 the roof, are discharged through the pipe *u*
with the water coming from the cooling
chamber *a*.

The water produced by the partial con-
densation of steam in the vaporizing cham-
ber *g*, is discharged through the pipe *j*.
45 It will be seen that the thread is protected
from the falling of drops of water by the
pipes *b* and by the slopes *h* as well as by the
inner drip pipes or gutters *m*.

It will be readily understood that the
50 chamber *a* in which water circulates, consti-
tutes a non-conducting casing which opposes
any thermic exchange by radiation or con-
vection between the chamber *g* receiving
55 steam for the treatment of the thread, and
the surrounding atmosphere.

Owing to the condensation of steam and
to the cooling of the pipes *b* through which
the threads pass (these pipes *b* being em-
bedded in the non-conducting chamber *a*),
60 the escape of steam through the holes *f* is
reduced. At the upper portion, the escape
of the steam contained in the chamber *c*, is
prevented by the flange *q* of the cover *p*,
65 which by dipping into the circulation cham-
ber *a*, constitutes a hydraulic seal.

What I claim as my invention and desire
to secure by Letters Patent is:—

1. In a device for treating threads with
vapor, a vaporizing chamber, a steam sup-
ply pipe projecting into the said chamber,
70 a roof having a double slope with eaves out-
side two walls of the said chamber, gutters
on the inner edges where the roof meets the
said walls, large openings in the said walls
for affording a passage for the thread, and
75 means for circulating water about said
chamber insuring condensation of steam.

2. In a device for treating threads with
vapor, a vaporizing chamber, a steam sup-
ply pipe projecting into the said chamber,
80 a roof having a double slope with eaves out-
side two walls of the said chamber, gutters
on the inner edges where the roof meets the
said walls, large openings in the said walls
for affording a passage for the thread, a 85
casing surrounding the said chamber, a
cupped cover closing the said casing, a dis-
charge pipe in the bottom of the chamber
and of the said casing, and means for cir-
90 culating water about said chamber insur-
ing condensation of the steam.

3. In a device for treating threads with
vapor, a vaporizing chamber, a steam sup-
ply pipe projecting into the said chamber,
95 a roof having a double slope with eaves out-
side two walls of the said chamber, gutters
on the inner edges where the roof meets the
said walls, large openings in the said walls
for affording a passage for the thread, a
100 casing surrounding the said chamber, a
cupped cover closing the said casing, a dis-
charge pipe passing through the bottom of
the chamber and of the said casing, a second
casing surrounding the first casing for form-
105 ing with the latter a refrigerating chamber,
pipes passing horizontally through the walls
of the first and second casing and located
opposite openings in the walls of the vapor-
izing chamber, covers outside for closing the
110 said pipes, openings in the covers for the
passage of the thread, and means for cir-
culating water in the refrigerating chamber.

4. In a device for treating threads with
vapor, a vaporizing chamber, a steam sup-
ply pipe projecting into the said chamber,
115 a roof having a double slope with eaves out-
side two walls of the said chamber, gutters
on the inner edges where the roof meets the
said walls, large openings in the said walls
for affording a passage to the thread, a
120 casing surrounding the said chamber, a
cupped cover closing the said casing, a dis-
charge pipe passing through the bottom of
the chamber and of the said casing, a second
casing surrounding the first casing for form-
125 ing therewith a refrigerating chamber,
pipes passing horizontally through the walls
of the first and second casing and located
opposite openings in the walls of the vapor-
izing chamber, covers outside for closing
130

the said pipes, openings in the covers for the passage of the thread, conduits in the cup-shaped cover for admitting water into the refrigerating chamber, openings in the 5 cover and in the wall of first casing for the passage of water and a discharge pipe in the bottom of the first and second casings.

In testimony whereof I have signed my name to this specification in the presence of two subscribing witnesses.

LOUIS EMILE ANDRÉ GILLIER.
